UNITED STATES PATENT OFFICE.

WILLIAM MACE McCAFFERTY, OF CARTERSVILLE, GEORGIA.

GARTER.

No. 912,718.

Specification of Letters Patent. Patented Feb. 16, 1909.

Application filed August 10, 1908. Serial No. 447,704.

To all whom it may concern:

Be it known that I, WILLIAM MACE McCAFFERTY, a citizen of the United States of America, and resident of Cartersville, county of Bartow, State of Georgia, have invented certain new and useful Improvements in Garters, of which the following is a specification.

My invention relates to that class of garters which are worn by men, above the calf of the leg, and next to the skin.

The object of my invention is a garter of this kind which may be laundered and which when in use maintains itself in position without chafing the leg or without causing the wearer discomfort. This object is attained by the means described in the specification and illustrated in the drawings, in which,

Figure 1 is a plan view of a garter embodying my invention. Fig. 2 is a perspective view showing the garter in use. Fig. 3 is a detail sectional view of a garter and a hose taken upon line x—x of Fig. 2.

The garter consists of a central body part, A, in the form of a depending strap formed integral with strips a, a', one of which has a button, B, secured to its end, and the other of which terminates in a series of button-holes, C, C'. The dependent strap, A, has secured to it a button, D, and a flap, E, with a button-hole for engaging the button, D. The body, A, and straps, a, a', are made of a light, flexible, strong, absorbent cloth, such as duck. The straps are made broad. The buttons are preferably tape buttons; that is, they are secured in place by loops of tape.

I have found that when the garter is put on about the leg, above the calf, with a degree of snugness which does not make the wearer conscious of the presence of the garter, that by reason of the lightness and the

flexibility of the cloth, it clings readily to the leg and prevents the slipping of the garter thereon. The hose is secured in place by drawing its upper end, G, over the depending strap, A and the button, D, turning the flap, E, down over the hose and passing the button and the hose into the button-hole of the strap, E.

A garter so constructed may be laundered time and again, as readily as other under garments, without impairing its utility.

What I claim is:

1. A garter consisting of a depending strap and straps for encircling the leg, all made from a flexible, non-elastic, washable cloth and means carried by the depending strap for engaging the hose. 55

2. A garter consisting of a depending hose-engaging strap, and straps for encircling the leg, the depending straps and the encircling straps being made from duck. 60

3. A garter consisting of a depending strap, means carried by the strap for engaging a hose, broad straps projecting from the depending strap for encircling the wearer's leg, means for connecting the ends of the encircling straps together, the depending strap and the encircling straps being made from non-elastic, washable cloth. 65

4. A garter consisting of a central depending wide washable strap, a button carried by the strap, a flap secured to the upper part of the depending strap and having a button hole for engagement with the button, cloth straps projecting from the depending strap for encircling the wearer's leg and means for securing the straps around the leg. 75 80
